JOSEPH P. LAWLOR AND JAMES I. SEAY, OF MEMPHIS, TENNESSEE.

MACHINE FOR MAKING CONCRETE BLOCKS.

Application filed September 1, 1926. Serial No. 132,940.

This invention has especial reference to a machine for making a comparatively short annular block, especially suitable for use as a section of a well strainer. The superposition of such blocks, one upon the other, and the necessity in such a structure as a well strainer of aligning them properly requires that an annular depression be formed in one end of the block and a complementary annular projection be made on the other end thereof and these features we have provided for in our machine. We have found that the outer portion of such strainer sections should be vertically corrugated to assist the water in flowing upward and downward therealong and that if such corrugations are a series of slots which are very narrow at their outer edge or where they open through the surface, an enlarge inward from the surface, they provide a better passage for the water.

The objects of our invention are primarily, to make a machine which will accurately form these sections or units and which will also accurately form in such units a series of inwardly enlarged slots, such as those hereinabove described.

The means by which these and other objects are accomplished and the manner of their accomplishment will be more fully hereinafter set out in the following description, on reference to the accompanying drawings, in which,—

Fig. 1 is a side elevation of our machine, the left half being in section on the center line and the right half in elevation, showing the machine set ready for a block to be cast therein, but with the top plate resting thereon instead of removed as it would be for filling the mold.

Fig. 2 is a sectional plan taken along the line II—II of Fig. 1.

Fig. 3 is a side view on a larger scale of one of the groove forming or core pins, and

Fig. 4 is a fragmentary section approximately full size taken on the line II—II of Fig. 1 with a portion of the stripper plate broken away to show the plate thereunder.

Referring now to the drawings in which the various parts are indicated by numerals, 1 is the base of the machine from which columns 2 extend upward and support an annular member 3. Resting on this annular plate, and secured thereto as by screws 4, 5 is a ring 5 having therethrough vertical holes 6 corresponding in number and spac-

ing to the number and spacing of the grooves which are to be formed in the concrete block. Disposed within each of these holes is a core pin 7. 8 is an annular plate having a number of holes corresponding in spacing to the holes in the ring 5, the holes in the plate 8 being shaped to conform to the cross sectional shape of the core pin 7. A similar plate 9 embraces the pins 7 at the upper surfaces of the ring 5. 10 are retaining pins one of which passes through the bottom of each of the core pins 7 immediately beneath the plate 8, the lower end of the pin 7 thus being confined between the plate 8 and the annular member 3.

Disposed above and resting on the ring 5 is the bottom plate 11 of the block mold, the upper surface of this plate being shaped to conform to the desired shape of the lower portion of the block to be formed thereon. This plate 11 has holes 12 therethrough corresponding in number and spacing to those in the ring 5 and carries at its upper edge a stripping plate 13 having a similar number of holes each shaped to accurately conform to the cross section of the core pin 7.

It will of course be understood that the plates 8, 9 and 13 might be dispensed with and the holes 6 and 12 in the ring 5 and plate 11 be made to conform to the shape of the core pin should it be so desired. The plates however have been introduced in this construction because of the greater facility with which the openings therein may be shaped to conform to the rod section, and for the further reason that should it be so desired, they may be tempered or hardened, this being especially desirable in the stripping plate 13 which is subjected to very considerable wear when the pins are withdrawn.

14 is an inner form preferably sectional and having a true cylindrical outer surface and 15 a holding member therefor. 16 is an outer form having an inner cylindrical surface preferably just touching the outer edge 7^a of the core pin 7. The outer form 16 may be made in a number of sections and secured in place by a retaining ring 17. 18 is an annular top plate shaped to conform to the desired upper end of the annular block to be formed. 19 is a cylindrical table hereinafter designated as a raising table, into which table are secured guide rods 20 which pass through suitable guiding holes in the member 3. The lower ends of these guide rods

- are secured to an annular plate 21 which is provided with suitable holes which are adapted to embrace the supporting rods 2 so that the plate 21 may slide on and be guided by these rods. 22 is a central post projecting downward from the plate 19 and resting on some form of raising means such as a screw jack 23 by which the table 19 may be raised and lowered.
- 19 Referring to Fig. 4 of the drawing, it will be seen that the cross section of the pins is roughly that of a sharply pointed egg with the thin side 7^A outward, and preferably in contact with the inner surface of the mold.
- 15 In Fig. 3 it will be seen that the pins each have a straight outer side 7^A, and that the upper ends thereof are of reduced area. Preferably the tapering of the pins is confined to the upper half, being that part which lies within the mold and forms the cores for the grooves in the blocks.

In operation the raising table 19 is lowered until the bottom 11 of the mold rests on the ring 5 with the core pins extending to the top of the mold and with their outer edges touching the inner surface of the outer form 16. The top plate 18 is removed. The mold is then filled with rather dry concrete, preferably a mixture of sand and cement only with little or no coarse particles, which is thoroughly tamped into place between and surrounding the core pins and is leveled off and shaped with the top plate, such material being added or removed as may be necessary 35 to allow this plate to seat solidly and yet the entire surface of the block to be smooth.

When this is satisfactorily completed the jack is operated and the mold raised to withdraw the pins longitudinally from the mold 40 and block. The forms are then stripped from the block, and it is removed to a storage and curing room where such further treatment is given as may be desired.

It will of course be understood that the 45 mold may be supported and the pins be lowered to withdraw them should it be so desired.

It will further be understood that any desired method of filling the mold may be used, 50 such for instance as with concrete placed by

centrifugal force in any usual and well known manner.

It will further be understood that the drawings are illustrative only and that various changes in detail may be made, and we 55 wish it distinctly understood that we do not wish to be limited to such details except as they may be set out specifically in the claims.

Having now fully disclosed the invention, what we claim is:—

1. In a machine for molding concrete blocks, the combination with means for shaping the exterior surfaces of a block, of means for forming channel-ways adjacent a surface of said block, comprising a plurality of pins, 65 each having one thin side, disposed within said shaping means, with said thin sides lying along and in contact with a shaping surface, and means for withdrawing said pins from said mold.

2. In a machine for molding concrete blocks, a mold comprising a bottom form and side forms, a plurality of pins projecting through said bottom form into said mold, means for withdrawing said pins from said 75 mold, and means for stripping said pins.

3. In a machine for molding concrete blocks, a mold having a bottom form and a cylindrical side form, and means for forming open channel-ways adjacent a surface of said block, comprising a plurality of egg-shaped pins projecting through said bottom form into said mold each of said pins having its thin side in contact with said side form, and means for withdrawing said pins longitudinally from said mold.

4. In a machine for molding concrete blocks, a mold comprising a bottom form and side forms, a plurality of pins secured to a common plate and projecting from said 90 plate through said bottom form into said mold, said bottom form closely embracing said pins, whereby they will be cleaned on removal, and means for separating said plate and bottom form to remove said pins from said mold.

In testimony of the foregoing, we affix our signatures.

JOSEPH P. LAWLOR.
JAMES I. SEAY.
